Paul Lesser, Island Park, N. Y., assignor to Calvine Cotton Mills, Inc., New York, N. Y., a corporation of New York

Application March 19, 1954, Serial No. 29,613

Term of patent 3½ years

(Cl. D92—1)

To all whom it may concern:

Be it known that I, Paul Lesser, a citizen of the United States, residing at Island Park, in the county of Nassau and State of New York, have invented a new, original, and ornamental Design for a Textile Fabric, of which the following is a specification, reference being had to the accompanying drawing, forming part thereof.

The single figure is a plan view of a piece of textile fabric showing my new design.

The design repeats itself as indicated over the entire surface of the fabric.

I claim:

The ornamental design for a textile fabric, as shown and described.
